TELEVISION ANTENNA

Marvin Kaplan, New York, N. Y., assignor to:
 Video Television, Inc., New York, N. Y., a corporation of New York

Application April 29, 1949; Serial No. 90,490

3 Claims. (Cl. 250—33.65)

1

This invention relates to television antennas, more particularly to receiving antennas having rigid dipole and reflector elements.

It is a common fault in many antenna constructions that, due to insufficient rigidity of the elements, a selected orientation cannot be maintained under strong wind conditions, and this is particularly true in antennas that are shipped disassembled and requiring on-the-spot attachments of the antenna components. Not only is there frequently such a lack of sufficient rigidity as to adversely affect the orientation of the entire antenna assembly, but there also is at times an unwanted movement between the two conductors in a dipole arrangement as well as between the reflector and antenna elements.

It is accordingly within the contemplation of my invention to provide an antenna structure of the class above-mentioned wherein the antenna components can be readily assembled into a rugged structure, the components being so firmly and securely held that they will not back up or otherwise move with respect to the antenna frame, under wind action. And in this aspect of my invention, it is an important object to provide an antenna in which the dipole antenna conductors are maintained in their pre-set longitudinal alignment, and the reflector components are maintained in proper parallel relation to the antenna elements.

The difficulties encountered in the storage, handling, shipping and erection of television antennas, particularly of the dipole H-frame construction, indicate that there is a great need for an adequately designed, inexpensive, foldable antenna structure, and capable of being readily assembled with a minimum of effort. It is accordingly an important object of my invention to provide a collapsible antenna having the advantages of compactness, rigidity and ease of assembly. And in this aspect of my invention, it is within my contemplation to provide a novel type of spring lock construction which will enable the components to be foldably swung into collapsed position for storage and shipping convenience, and to be readily unfolded and locked rigidly into an operative position by a quick manipulative effort.

With the last-mentioned objective in view, I have constructed several forms of foldable antennas, according to the present invention, which I have found could be assembled in a matter of seconds, to produce a rigid antenna structure having the advantages and features hereinabove mentioned. These devices, as will appear from

2

the following description, are compact when collapsed, are very efficient when operatively installed, and are simple and relatively inexpensive to fabricate.

Other objects, features and advantages will appear from the drawings and the description hereinafter given.

Referring to the drawings:

Figure 1 is a plan view of one form of my invention shown in its open operative condition.

Figure 2 is a side view of Figure 1.

Figure 3 is an enlarged section of Figure 2 taken substantially along line 3—3.

Figure 4 is a fragmentary plan view of Figure 15 3, the dot-dash lines showing the element partially removed from the spring lock member.

Figure 5 is a section of Figure 4 taken along line 5—5, but showing the element in the dot-dash position.

Figure 6 is a plan view of the frame of Figure 1 shown in its folded condition.

Figure 7 is a fragmentary plan view of a dipole antenna and support, showing a modified form of my invention.

Figure 8 is a section of Figure 7 taken substantially along line 8—8 thereof.

Figure 9 is a fragmentary sectional elevation of an element and support, therefore in disassembled relation, illustrating another modification of my invention.

Figure 10 is a fragmentary plan view of Figure 9.

Figure 11 is a sectional elevation of the components of Figure 9 shown in assembled relation.

Figure 12 is a disassembled part sectional plan view of an element and support in accordance with still another modification of my invention.

Figure 13 is an elevation of Figure 12.

Figure 14 is a part sectional elevation of the 40 assembled components of the device of Figures 12 and 13.

In the form of my invention illustrated in Figures 1 to 6, an H-frame structure is shown, the main members of which are the antenna elements assembly 20, the reflector elements assembly 21, and the cross beam 22, the latter being mounted upon the mast 23 by securing means such as the conventional U-bolt fastener 24.

The antenna element assembly 20 comprises, in 50 the form illustrated, the tubular elements 25 and 26 of conducting material such as an aluminum alloy, and the dielectric support or block 27 preferably made of a suitable water resistant material, such as a Bakelite plastic. Each of the elements 25 and 26 is pivotally mounted by rivets 28

and 29 upon the block 27, and rigidly secured thereto by the spring lock members 30 and 31 in a manner to be more clearly hereinafter set forth. The arrangement is hence such that the two elements 25 and 26 are maintained by the spring locks 30 and 31 in substantial longitudinal alignment, thereby constituting a dipole antenna. Similarly, the reflector assembly 21 comprises the preferably tubular conductors 32 and 33, these being pivotally attached by pivotal rivets 34 and 35 to the metallic support or plate 36. The spring lock members 37 and 38 are adapted to hold the elements 32 and 33 in substantial longitudinal alignment when in their operative positions in the manner illustrated. The dipole antenna 20 and the reflector assembly 21, when properly secured to the cross beam 22, together constitute the aforesaid H-frame structure, the reflector elements 32 and 33 being in spaced relation and parallel to the antenna elements 25 and 26.

It is preferred that the inner terminals 39 and 40 of the antenna elements 25 and 26, respectively, be of flattened construction, so as to be able to rest flat against the upper flat surface of the block 27.

The spring locks 30, 31, 37 and 38 are each of substantially similar construction, each being of substantial channel-like configuration comprising an intermediate wall 41, legs 42 and 43 at right angles to intermediate wall 41 and extending downwardly therefrom, anchor wall 44 connecting leg 43 and retaining flange 45, and the outwardly extending inclined lip 46 disposed oppositely with respect to anchor wall 44. A rivet 47 extends through the anchor wall 44 and the block 27, (or in the case of the reflector assembly, through the analogous plate 36). A stud 48 extends through the block 27 and through the hole 49 in the intermediate wall 41 of the spring lock member, the wing nut 50 being in threaded engagement with the extending portion of the shank of the stud. Electrically connected to the intermediate wall 41 of the spring lock is the conventional lug 51 which joins the transmission line 52 of the television receiver. The said lug 51 may be of the washer type, whereby the wing nut (or head of the stud) is in pressing engagement therewith to establish a firm contact, and thereby effect an electrical connection with the spring lock and the antenna element operatively in engagement therewith.

As aforesaid, the spring locks 37 and 38 on the reflector assembly are substantially like those on the antenna dipole. However, there obviously is no need for a transmission line at this point, and hence the employment of a stud and wing nut assembly, such as elements 48 and 50, are dispensed with.

The proportions of the channel of each spring lock member are such that the element engaged thereby will be completely enveloped and engaged by walls 41, 42 and 43 and the adjacent support, such as the block 27 or the plate 36. In other words, referring to Figure 3, it will be seen that when the flattened terminal 39 of the antenna element 25 is in operative engagement with the spring lock 30, the intermediate wall 41 and the upper surface of block 27 are in contact with the top and bottom surface of terminal 39, and the vertical walls or legs 42 and 43 are in abutment with the lateral edges of the flattened terminal 39. It is thus apparent that once an element, whether it be an antenna element 25 or 26, or a reflector element such as 32 and 33, is operatively in place, it will be held by the said legs

42 and 43 against lateral shifting or displacement, and by the wall 41 and the underlying support against vertical displacement. It has been found that the vibrations of the mast due to wind pressure will not adversely affect the rigid connection thus established and, accordingly, the antenna elements and reflectors will maintain their selected orientation and mutual positioning as long as the crossbeam 22 is held in position, the latter being readily accomplished by known conventional attachments. It has also been found that the employment of the spring lock above-described completely eliminates the disadvantages of insecure holding inherent in friction locks, since the legs 42 and 43 provide a positive locking means to prevent displacement.

In its collapsed condition, the antenna elements 25 and 26, and the reflector elements 32 and 33, are disposed substantially parallel to the crossbeam 22, as clearly shown in Figure 6. In this condition, the said elements are substantially normal to the block 27 and plate 36, respectively, antenna element 25 being adjacent reflector element 32, and antenna element 26 being adjacent reflector element 33. It is apparent that in this form of my invention there are no detached parts, and the only detachable parts are the stud and wing nut elements 48 and 50 associated with the spring locks 30 and 31.

To install this unit, all that need be done is to swing outwardly the elements 25, 26, 32 and 33 until the transverse slotted portions 53 at the inner ends of the elements come into engagement with the shanks of the coacting studs 48. During such rotative movement of the elements, each inner terminal portion thereof comes into engagement with the inclined entrance wall or lip 46 of the coacting spring lock, producing a yieldable lifting of the entrance portion of the spring lock, the anchorage at 47 rigidly holding the inner portion of the lock against the underlying support. In other words, since the entrance portion of each of the spring locks is disposed outwardly with respect to the entire frame assembly, the outwardly extending terminal of each of the elements will, upon being operatively swung into position, produce a lifting of the lip 46, the leg 42 and the outer portion of intermediate wall 41, due to the cam action of the inclined wall of said lip 46. The entire lock will snap downwardly when the element reaches its operative position with the said slotted portion 53 in engagement with the stud 48. In this position, the elements on the respective supports 27 and 36 are in substantially longitudinal alignment.

It is thus apparent that the entire operation of bringing the components of the antenna frame into operative position is merely a matter of seconds. The attachment of the frame to the mast is a separate operation which can readily be effectuated in well-known and conventional manner.

As aforesaid, when the components are in their final assembled position, the elements are rigidly maintained against displacement by the walls of the spring lock; and this has been accomplished by a simple manual manipulation, without the use of tools or special fastening members. Reliance is not placed solely upon the stud 48 and nut 50 for holding the element in place, particularly in view of the fact that the legs 42 and 43 serve this purpose independently of the said stud and wing nut.

It is particularly pertinent to note that not only does the spring lock arrangement permit

ready movement of the components into their operative positions, and at the same time effect a secure maintenance of these components in their final positions, but they also serve the purpose of permitting a quick retraction of these elements into their folded positions by the simple expedient of lifting the spring lock members at their entrance portions, that is, by lifting the lip 46 to permit withdrawal of the element from within the said spring lock.

Figures 7 and 8 illustrate a somewhat modified form of the invention above-described. Here the support 55 is shorter than the analogous parts above-described, and accommodates at the upper and under surfaces thereof spring locks 56 and 57 operatively maintaining therein, in the manner aforesaid, the oppositely disposed elements 58 and 59. In this form, the elements are in longitudinal alignment, but at slightly different levels, and obviously presents a more compact arrangement. Here a terminal lug 60 for the transmission line is shown attached to the pivotal connection 61, thereby dispensing with the stud and wing nut assembly above-described. It is of course understood, however, that a stud and wing nut may, if desired be employed in the manner above-described.

A modified form of my invention is disclosed in Figures 9 to 11, wherein a tubular support 62 is used in place of the flat block and plate 27 and 36 of the form of my invention above-described. The support 62 is of insulating material when employed with antenna elements and of conducting material when employed with reflectors, just as in the first form herein described. It contains an axial bore 63 for accommodating the tubular inner terminal such as 64 of the antenna element 65, instead of a flattened terminal element. The support 62 has secured thereto the diametral rivet shank 66 to one terminal 67 of which is anchored the spring clip 68 from which depends the lock pin 69 extending through the opening 70 in support 62. The terminal 64 of element 65 contains at its inner end the open slots 71 and spaced inwardly therefrom the lock pin hole 72.

In assembling the element 65 into the support 62, the terminal 64 enters the bore 63, a slot 71 either straddling the lock pin 69 or being disposed on one side thereof. In either event, the said lock pin 69 will be urged upwardly when the extremity of terminal 64, or the end 73 of slot 71, comes into engagement therewith, thereby permitting a further inward movement of the element 65 until it engages the rivet shank 66. A slight turning of element 65 may be necessary to bring slots 71 into straddling relation with the said shank, whereupon it will be forced therepast into its final position illustrated in Figure 11. In this position, the lock pin 69 has been urged downwardly by spring 68 into the hole 72.

It is apparent that in this manner the element 65 is firmly locked within the support 62, and cannot move either longitudinally or rotatively with respect thereto. The lug 74, connected to the transmission line, is electrically connected to the rivet 66, and thereby establishes an electrical connection with the antenna element directly through the rivet, as well as through the spring clip 68 and the pin 69. It is also apparent that a ready detachment of the element 65 can be effected merely by raising the spring clip 68, which will remove the pin 69 from its engagement with hole 72, and thereby permit a retraction of the element 65.

In the form of my invention illustrated in Figures 12 to 14, the support 75 is substantially like support 62 above-mentioned, containing an axial bore 76 adapted to receive the cylindrical terminal 77 of the element 78. Tubular support 75 contains a diametral rivet 79, to one end 80 of which the terminal lug 81 is secured to effect an electrical connection to a transmission line. The inner end of terminal 77 contains the open opposite bayonet slots 82, and a diametral pin 83 upon which is anchored the inwardly extending spring 84.

In assembling this form of my invention, the terminal 77 of element 78 is inserted within bore 76 until the slots 82 engage the shank of the rivet 79. A continued movement longitudinally will bring the spring 84 into engagement with said shank, so that when the bayonet off-sets 85 of slots 82 reach the shank, and the element 78 is rotated to create an interlocking engagement between the shank and the said bayonet slots, the spring 84 will yieldably hold the element 78 firmly engaged within the support 75. When such mechanical attachment is effected, there will also be a firm electrical connection, particularly in view of the action of said spring 84.

It is obvious that the attachment as well as detachment of element 78 with respect to support 75 can be effectuated by a simple manipulative effort without the use of tools or separate fastening elements.

In the above description, the invention has been disclosed merely by way of example and in preferred manner; but obviously many variations and modifications may be made therein which will still be comprised within its spirit. It is to be understood, therefore, that the invention is not limited to any specific form or manner of practicing same, except insofar as such limitations are specified in the appended claims.

I claim:

1. In an antenna construction, a support, at least one rigid conductor element pivotally mounted on the support, and a spring lock secured to the support and releasably holding a terminal portion of said element in engagement therewith when said element and support are in a preset relative position, said spring lock having a channel-like body portion, one side of the lock being attached to the support, the opposite side being free whereby it constitutes an entrance side, said channel-like body portion having an intermediate wall spaced from the support and two depending legs at said respective attached and free sides of the said spring lock, the said intermediate wall being yieldably urged towards the support, the said terminal portion of the element being adapted, upon an operative pivotal movement of the element, to enter said channel-like body portion through said entrance side, the distance between said two legs being sufficient to accommodate therebetween the said terminal portion when the element and the support are in said preset relative position, the said support and intermediate wall having apertures in registry, and a fastening member extending through said apertures, the said terminal portion of the element having a slotted portion engageable with said fastening member when the terminal portion is operatively disposed within the lock.
2. A dipole antenna in combination with a reflector comprising a cross beam, a support rigidly secured to one end of the crossbeam, a second support rigidly secured to the other end of the

cross beam, a rigid conductor element pivotally mounted on the first-named support, a spring lock secured to the first-named support and releasably holding a terminal portion of the element in engagement therewith when the element and support are in a preset relative position, said spring lock having a channel-like body portion, one side of the lock being attached to the support, the opposite side being free whereby it constitutes an entrance side, said channel-like body portion having an intermediate wall spaced from the support and two depending legs at said respective attached and free sides of the said spring lock, the said intermediate wall being yieldably urged towards the support, the said terminal portion of the element being adapted, upon an operative pivotal movement of the element, to enter said channel-like body portion through said entrance side, the distance between said two legs being sufficient to accommodate therebetween the said terminal portion when the element and the support are in said preset relative position, the said support and intermediate wall having apertures in registry, and a fastening member extending through said apertures, the said terminal portion of the element having a slotted portion engageable with said fastening member when the terminal portion is operatively disposed within the lock, and another spring lock secured to second support and releasably holding a terminal portion of said reflector.

3. In an antenna construction, a flat support having opposite portions, a pair of rigid conductor elements pivotally mounted on said opposite portions of the support, said elements having flat terminal portions in substantially flush engagement with said support when the elements extend in opposite directions, and spring locks secured to said opposite portions of the support and releasably holding said terminal portions in engagement therewith when the elements and support are in a preset relative position, each of said spring locks having a channel-like body portion, one side of the lock being attached to the support, the opposite side being free whereby it constitutes an entrance side, said channel-like body portion having an intermediate wall spaced from the support and two depending legs at said respective attached and free sides of the said spring

lock, the said intermediate wall being yieldably urged towards the support, the said terminal portions of the elements being adapted, upon operative pivotal movement of the elements, to enter such channel-like body portions through such entrance sides, the distance between said two legs being sufficient to accommodate therebetween a terminal portion when the elements and the support are in said preset relative position, the said support and intermediate wall having apertures in registry, and a fastening member extending through said apertures, each of the said terminal portions of the elements having a slotted portion engageable with said fastening member when the terminal portions are operatively disposed within the locks.
